Lane, New Hyde Park, N.Y. 12538

Filed Mar. 24, 1966, Ser. No. 1,615

Term of patent 7 years

(Cl. D87—5)

FIG. 2 is a side elevational view thereof.

FIG. 3 is a front elevational view thereof.

FIG. 4 is a side elevational view opposite to the view of FIG. 2.

FIG. 5 is a perspective view thereof.

FIG. 6 is a perspective open view with the wig block support in the foreground.

FIG. 7 is a fragmentary top perspective view of a wig container embodying another form of our new design wherein a rigid handle is employed thereon in lieu of a flexible handle.

The dominant features of our design reside in the full line portions of the drawing.

We claim:

The ornamental design for a wig container, substantially as shown and described.
